UNITED STATES PATENT OFFICE.

JOSEPH MORSTATT, OF ASTORIA, NEW YORK, ASSIGNOR OF ONE-HALF
TO ZOLTAN MOSHKOVITZ, OF NEW YORK, N. Y.

CIGAR-BOX.

SPECIFICATION forming part of Letters Patent No. 761,780, dated June 7, 1904.

Application filed February 1, 1904. Serial No. 191,417. (No model.)

To all whom it may concern:

Be it known that I, JOSEPH MORSTATT, a citizen of the United States, residing in Astoria, borough of Queens, New York city, in the county of Queens, State of New York, have invented certain new and useful Improvements in Cigar-Boxes, of which the following is such a full, clear, and exact description as will enable any one skilled in the art to which it appertains to make and use the same, reference being had to the accompanying drawings, forming part of this specification.

My invention relates to certain improvements in a box adapted to hold cigars or like articles, which are generally arranged in layers, and certain parts of the improvements relate more particularly to such a box, which is known as "non-refillable" and which is a well-known article particularly designed to prevent the unfair or fraudulent practice of a dealer substituting inferior articles or cigars in the box or substituting a different brand from that marked on the box.

I have illustrated a type of my invention in the accompanying drawings, wherein—

Figure 1 is a perspective view of my improved box shown with the lid raised and as being filled with cigars, with the revenue or other stamp or mark on the front side of the box intact in so far as its mutilation is concerned by the mutilating device, which is hereinafter described. Fig. 2 shows in perspective one corner of the box after the same has been emptied of its cigars and with the revenue stamp or other mark upon its exterior shown as acted upon by the mutilating device. Fig. 3 is a vertical cross-section taken centrally through the box with the lid raised as shown in Fig. 1. Fig. 4 is a horizontal sectional view of the box shown in Fig. 3, the plane of the section being indicated by the line 4-4, Fig. 3. Fig. 5 is a vertical central section of the body of the box, the plane of the section being indicated by the line 5-5, Fig. 3, and the view taken in the direction of the arrows. In this view the contents of the box are shown as reduced to the last layer, upon the removal of which the mutilating device comes into play, as hereinafter described.

Fig. 6 is a perspective view of the mutilating device acting in conjunction with the slot in the side of the box, over which slot the revenue stamp is placed, the view being shown on a somewhat enlarged scale. Fig. 7 is a detail view of a portion of the follower and one of its spring-arms for forcing it outwardly and engaging the teeth on the follower.

Referring to the drawings, in which like numbers of reference designate like parts throughout, 1 designates a box of a rectangular shape like that ordinarily used for cigars. Within the interior of the box is a loosely-fitting follower or false bottom 2, which in the construction shown consists in a thin solid board of wood or other suitable material, upon the back of which are formed sets of locking teeth or notches 3, one set of such teeth being disposed near each corner of the rectangularly-shaped follower and extending in a line substantially diagonal thereon, as shown in Fig. 4. These teeth or notches 3 are engaged by the respective ends of four spring-arms 4, which project outwardly toward each corner of the box and curve upwardly, each of said springs acting to push upon the back of the follower and force it up toward the top of the box. These four spring-arms 4 are provided by using two flat steel springs of a bow shape, with the bow extending downwardly into the box and the two pieces being crossed X-shaped in the bottom of the box and secured therein and to each other by a suitable rivet 5. The normal position of the follower 2 is shown in Figs. 3 and 4, where it lies at the lowest point in the bottom of the box, with the springs 4 flattened out and engaging the teeth 3 near the outer end of each set thereof, and the follower may be locked and maintained in this depressed position by means of a locking-pin 6, which lies in a groove 7 on the under side of the box, and is passed through a pair of eyes 8,8, projecting through holes 9 in the bottom of the box and being fastened in the back of the follower 2, as shown in Figs. 3 and 4. When thus temporarily locked at its lowest point, the box is then filled with cigars and sealed up in the usual way, after which the locking-pin 6 is withdrawn

by the manufacturer before the box is put on the market.

The cigars shown at 10 in the box are kept from being forced out of the box by the follower by means of a retaining device 11, which in the present instance consists in a thin metallic band or strip placed centrally across the top of the box and secured suitably to the interior of the opposite ends thereof, so as to lie flush with the upper edges of the same, as shown in the drawings. This band may be fastened in place by means of a suitable flange 12 on each end, being tacked or riveted to the sides of the box. This band should be of a tough and sufficiently rigid material to keep the cigars in place, and it should only be of a width necessary for it to securely hold the cigars, at the same time not to cover or conceal them, so that any one in looking at the cigars in the box can get a sufficiently full view of them.

The box is provided with a lid 13, which is hinged at 14 to one edge of the box, and one side of the box, preferably the front side, is formed with an opening at 15, which in the present instance is made by reducing the height of the front side of the box, and this opening practically exposes the ends of the upper layer of cigars in the box, as will be understood more particularly from Figs. 1 and 3, so that the cigars may be extracted from the box by drawing them endwise through the opening 15. The opening 15 is closed by a suitable cover 16, which is made to snugly fit the opening, and in the present instance it is secured to the front edge of the lid 13, on which it forms practically a downwardly-projecting flange, so that on closing the lid 13 of the box the opening 15 is at the same time closed by the cover or part 16 on the lid. This opening in the upper part of the box affords a ready means for withdrawing the cigars from beneath the retaining-band 11, and the cover 16 for such opening may or may not be part of the lid, as shown.

The follower 2 is constantly pressed outwardly toward the opening in the top of the box, and as soon as one layer of cigars has been withdrawn the follower forces the remaining lot upwardly toward the top, so that the next subjacent layer becomes the uppermost one, and so on until the last layer of cigars is forced uppermost, as shown in Fig. 5. When this last layer of cigars is removed, the follower moves practically to the top of the box, as shown in Fig. 2. In this connection it should be noted that by virtue of the particular shape of the teeth 3 of each of the sets of teeth engaged by the ends of the spring 4 it is not possible to depress the follower 2 at any point of its movement, and this is intended to prevent any one from tampering with the box, so as to push back the follower and refill the box.

65 The mutilating device comprises an oblique

slot 17 in the front side of the box, near one end thereof, and it is adapted to be covered upon the exterior thereof with an ordinary revenue stamp or other such mark 18, which is usually placed on a box of cigars. Within 70 the interior of the box is a flat spring-arm 19, secured at 20 to the bottom of the box, and its free end carries a suitable projection or pin 21, which projects through a slot 17 and sufficiently far upon the exterior of the box 75 to pass through or puncture the stamp 18 placed over said slot. When the spring-arm 19 is retracted, it lies flat in the bottom of the box, as indicated in the several views; but as soon as it is released it flies upwardly, thereby carrying its pin or projection 21 practically through the length of the slot 17, so that it stands at the upper end thereof, as shown in Fig. 2. When this movement occurs, the stamp 18, placed over the slot, is torn 80 and mutilated a distance the length of the slot, as indicated in Fig. 2. This mutilation, however, does not take place by degrees, but only when the follower has reached its outward limit, which occurs when the last layer 85 of cigars has been removed. This mutilating device is maintained in locked position throughout the outer movement of the follower by means of a locking-arm 22, which is pivoted in the bottom of the box at 23 90 and is constructed to lie over upon a part of the spring-arm 19, as shown particularly in Fig. 6, and to itself be engaged by a traveling finger or member 24, which is pivoted at 25 in the bottom of the box. This finger 24 100 is not quite a length that is equal to the depth of the box, but it is such a length that it remains in inclined position throughout the outer movement of the follower upon the back of which the free end of the finger bears and against which it is held by means of the tendency of the locking-arm 22 to rise upwardly under the constant spring-pressure of the arm 19. The continued oblique position of the traveling finger 24 keeps the locking-arm 22 105 down, as will be particularly understood from Figs. 5 and 6, and holds it in this position until the arm 24 can move into practically vertical position, at which time the locking-arm 22 is free to rise. As soon as the last 110 layer of cigars (shown in Fig. 5) is removed, the follower is forced practically to the top of the box, and the traveling finger 24, which constantly moves after it, is then free to be turned into vertical position by the locking-arm, which latter thereby releases itself, whereupon the spring 19 with a single stroke forces the pin 21 through the stamp 18 and mutilates it, as indicated in Fig. 2.

As the revenue regulation in regard to the cancellation or destruction of revenue stamps on cigar-boxes does not require the revenue stamp to be destroyed until the box is emptied of its contents, my invention in this respect has the important advantage of not mutilat- 115 120 125 130

ing and destroying the stamp until practically the last cigar is removed from the box, for it will be noted that the follower or false bottom 2 controls the device for restraining the 5 action of the mutilator and prevents it from acting until the follower reaches the top of the box, which cannot occur until practically all of the cigars have been removed, whereupon at a single stroke the mutilator acts and 10 cuts and tears the stamp throughout a considerable portion thereof. It will be also noted that in addition to the retaining device 11 keeping the cigars on a level within the box against the action of the follower this 15 device also renders it more difficult for the fraudulent refilling of the box with which it is used, as it serves as an additional obstruction or guard for the open part of the box and prevents the refilling of the box. The 20 opening 15, through which the cigars are extracted endwise from the box, is also a convenient arrangement that possesses obvious advantages.

While I have shown the follower 2 as a solid 25 board, it of course may take any suitable form and be made of open-work, if desired; but the solid construction is preferable.

I wish it to be understood that I do not limit 30 my invention to the specific constructions of the various parts herewith shown, as it is evident that modifications may be made in the same, respectively, without departing from the spirit of the invention.

Having thus described my invention, what 35 I claim, and desire to secure by Letters Patent, is—

1. The combination of a box adapted to contain articles in layers and provided with a spring-pressed follower for pressing the 40 contents of the box toward the top thereof, a retaining device extending across the upper part of the box to retain the contents therein against the pressure of the follower, one side of said box at or near its upper part being 45 provided with an opening in a plane practically parallel with said layers and through which a portion of the upper layer of the contents of the box may be extracted endwise, substantially as and for the purpose set forth.

50 2. The combination of a box adapted to contain articles in layers and provided with a spring-pressed follower for pressing the contents of the box toward the top thereof, a retaining device extending across the upper 55 part of the box to retain the contents therein against the pressure of the follower, one side of said box at or near its upper part being provided with an opening in a plane practically parallel with said layers and through 60 which a portion of the upper layer of the contents of the box may be extracted endwise, and a removable cover for said opening through which the contents are extracted, substantially as and for the purpose set forth.

65 3. The combination of a box adapted to con-

tain articles in layers and provided with a spring-pressed follower for pressing the contents of the box toward the top thereof, a retaining device extending across the upper part of the box to retain the contents therein 70 against the pressure of the follower, one side of said box at or near its upper part being provided with an opening in a plane practically parallel with said layers and through which a portion of the upper layer of the contents of the box may be extracted endwise, a removable cover for said opening through which the contents are extracted, and a movable lid for said box, said lid being connected with the cover for said opening and acting to 75 open said cover when the lid is opened, substantially as and for the purpose set forth.

4. The combination of a box adapted to contain articles in layers and provided with a spring-pressed follower for pressing the contents of the box toward the top thereof, a retaining device extending across the upper part of the box to retain the contents therein against the pressure of the follower, one side of said box at or near its upper part being 80 provided with an opening in a plane practically parallel with said layers and through which a portion of the upper layer of the contents of the box may be extracted endwise, a movable lid for the top of said box, a cover 85 for said opening through which the contents are extracted, said cover being secured to end edge of said lid, substantially as and for the purpose set forth.

5. The combination of a box adapted to contain articles in layers and provided with a spring-pressed follower for pressing the contents of the box toward the top thereof, a retaining device extending across the upper part of the box to retain the contents therein 90 against the pressure of the follower, the upper edge of one side of said box being cut away to constitute an opening in a plane practically parallel with said layers and through which a portion of the upper layer of the contents of the box may be extracted endwise, a 95 lid hinged to one side of the box opposite to the cut-away side and having its front edge provided with a downwardly-extending piece adapted to fit the said opening as a cover when 100 the lid is closed, substantially as and for the purpose set forth.

6. The combination of a box adapted to contain articles in layers and provided with a spring-pressed follower for pressing the contents of the box toward the top thereof, a retaining band or strip extending across the upper part of the interior of said box so as to retain the contents therein against the pressure of the follower but not to conceal such 115 contents, the said band being made of a sufficiently tough and rigid material for resisting the pressure thereon, the said box being provided with a suitable opening in a plane practically parallel with said layers and through 120 125 130

which a portion of the contents lying uppermost in the box may be extracted endwise from under said retaining-band, substantially as and for the purpose set forth.

7. The combination of a box adapted to have the contents thereof arranged in layers such as cigars, a spring-pressed follower arranged within the box beneath said contents and serving to press the same toward the open part thereof, the said follower gradually moving toward the open part of the box as the layers of contents are reduced, a mutilating device adapted when released to mutilate or destroy the revenue or other stamp or mark upon the exterior of the box, the said mutilating device being normally held from action by the presence of the contents of the box and until practically the last layer thereof has been extracted, said mutilating device then being released and acting upon said stamp or mark, substantially as and for the purpose set forth.

8. The combination of a box adapted to have the contents thereof arranged in layers such as cigars, a spring-pressed follower arranged within the box beneath said contents and serving to press the same toward the open part thereof, the said follower gradually moving toward the open part of the box as the layers of contents are reduced, a mutilating device adapted when released to mutilate or destroy the revenue or other stamp or mark upon the exterior of the box, the said mutilating device being normally held from action by the position of the follower and until the follower has moved practically to the top of the box after the extraction of the last layer of contents, said mutilating device being then released and acting to mutilate or destroy said stamp or mark, substantially as and for the purpose set forth.

9. The combination of a box adapted to have the contents thereof arranged in layers such as cigars, a spring-pressed follower arranged within the box beneath said contents and serving to press the same toward the open part thereof, the said follower gradually moving toward the open part of the box as the layers of contents are reduced, a spring-actuated mutilating device for mutilating or destroying a revenue or other stamp or mark upon the exterior of the box, locking means normally holding said mutilating device retracted and provided with a traveling member or finger which travels after said follower and serving to keep the locking means locked throughout such movement and until the follower has reached its outermost position, the said traveling member or finger then acting to release said locking mechanism of the mutilating device, substantially as and for the purpose set forth.

10. The combination of a box adapted to have the contents thereof arranged in layers such as cigars, a spring-pressed follower arranged within the box beneath said contents

and serving to press the same toward the open part thereof, the said follower gradually moving toward the open part of the box as the layers of contents are reduced, a spring-actuated mutilating device, a pivoted arm adapted to engage said mutilator and normally hold it against the action of its spring, a traveling member or finger adapted to be engaged by said locking-arm and to maintain the same locked while said finger travels after the follower and until said follower reaches its outermost position, the said finger then releasing the arm to unlock said spring-actuated mutilating device, substantially as and for the purpose set forth.

11. The combination of a box adapted to have the contents thereof arranged in layers such as cigars, a spring-pressed follower arranged within the box beneath said contents and serving to press the same toward the open part thereof, the said follower gradually moving toward the open part of the box as the layers of contents are reduced, said box being provided with a slot in a suitable part thereof and over which a revenue or other stamp or mark is placed upon the exterior of said box, a mutilating device for said stamp or mark comprising a spring arranged within the box and provided with a projection or pin extending through said slot and into said stamp or mark covering the slot, a pivoted locking-arm adapted to normally engage said spring to hold it in retracted position, a pivoted traveling member or finger adapted to normally engage said locking-finger to hold it in locked position as said finger or member travels after the follower and until the follower has reached its outermost position, the said finger or member then serving to release said locking-arm to permit said spring to force its pin or projection through said stamp or mark to mutilate or destroy the same, substantially as and for the purpose set forth.

12. The combination of a box adapted to have the contents thereof arranged in layers such as cigars, a spring-pressed follower arranged within the box beneath said contents and serving to press the same toward the open part thereof, the said follower gradually moving toward the open part of the box as the layers of contents are reduced, said box being provided with a slot in a suitable part thereof and over which a revenue or other stamp or mark is placed upon the exterior of said box, a mutilating device for said stamp or mark comprising a spring secured by one end in the bottom of the interior of the box and provided at its free end with a pin or projection extending through said slot and into the stamp or mark covering the slot upon the exterior of the box, a pivoted locking-arm adapted to overlap said spring when the same is depressed or retracted, a pivoted traveling finger or member pivoted by its lower end to the bottom of the box and engaging with its free end

the back of the follower and being of such length as to be maintained in inclined position during the outward movement of the follower and until the follower reaches its outermost 5 position and said finger or member serving when in inclined position to keep the locking-arm in locked position but to release the same when said finger or member is free to assume a practically vertical position, substantially as 10 and for the purpose set forth.

13. The combination of a box adapted to contain articles in layers and provided with a spring-pressed follower for pressing the contents of the box toward the top thereof, a retaining device extending across the upper part 15 of the box to retain the contents therein against the pressure of the follower, one side of said box at or near its upper part being provided with an opening in a plane practically parallel 20 with said layers and through which a portion

of the upper layer of the contents of the box may be extracted endwise, and a mutilating device adapted when released to mutilate or destroy the revenue or other stamp or mark upon the exterior of the box, the said mutilating device being normally held from action by the presence of the contents of the box and until practically the last layer thereof has been extracted, said mutilating device then being released and acting upon said stamp or 25 mark, substantially as and for the purpose set forth.

In testimony whereof I have hereunto set my hand, this 28th day of January, 1904, in presence of the two subscribing witnesses. 35

JOSEPH MORSTATT.
